G. McARTHUR.
RIVET CLUB DOLLY.
APPLICATION FILED APR. 24, 1919.

1,326,518.

Patented Dec. 30, 1919.

UNITED STATES PATENT OFFICE.

GEORGE McARTHUR, OF BAYONNE, NEW JERSEY.

RIVET CLUB-DOLLY.

1,326,518.

Specification of Letters Patent. Patented Dec. 30, 1919.

Application filed April 24, 1919. Serial No. 292,827.

To all whom it may concern:

Be it known that I, GEORGE McARTHUR, a citizen of the United States, and a resident of Bayonne, county of Hudson, and State of New Jersey, have invented certain new and useful Improvements in Rivet Club-Dollies, of which the following is a specification.

My improvements relate to means for sustaining one end of a rivet while the other 10 is being upset or hammered into shape, as in the assembling of metallic structures for buildings, ships, bridges, etc., the object being to afford a tool or implement specially adapted to the purpose that may be quickly 15 and conveniently applied and manipulated, and in which provision is made for adjusting it to the varying requirements of use as set forth in Letters Patent No. 1,172,894, issued to me Feb. 22, 1916,—the present invention being supplemental to that therein disclosed, in which a fulcrum bar is used in connection with the actuating lever by which the dolly proper is manipulated.

My present invention provides for the use 25 of an auxiliary dolly bar to be used in conjunction with the actuating lever as a spring "club" dolly, the actuating lever being supported in a fulcrum stirrup on a flexible suspender which is attached temporarily to 30 any available stationary support, so that my spring club dolly bar may be conveniently manipulated to sustain one end of a rivet while the other is being headed in a manner well known in the art, and provision being 35 made for the mounting of the spring club dolly on the actuating lever in alinement with the longitudinal axis of the latter, or at right angles thereto, as hereinafter more fully set forth.

40 In the accompanying drawings,

Figures 1 and 2, are elevations of the actuating lever, taken at right angles to each other;

Fig. 3, is a side elevation; and

45 Fig. 4, an edge elevation of my spring club dolly bar;

Fig. 5, is what may be designated as a top view of the implement as used against a horizontal bolt or rivet;

50 Fig. 6, is a sectional elevation taken upon plane of line 6—6, Fig. 5;

Fig. 7, is a view showing the seating of the actuating lever in the fulcrum stirrup;

55 Fig. 8, is a view illustrating the use of device in the support of a rivet in axial alinement with the lever;

Fig. 9, is a similar view showing the use of the device to sustain a rivet positioned substantially at right angles to the longitudinal axis of the actuating lever. 60

Fig. 10, is a side elevation of the dolly bar, showing a modification.

The actuating lever A, is essentially the same as that shown and described in my aforesaid Letters Patent No. 1,172,894, the 65 preferred form of lever socket head α^x , being bifurcated or open-ended as in Figs. 9 and 10, of said patent. In fact my spring club dolly bar D, is in the nature of an alternative to the dolly bar and fulcrum bar 70 shown and described therein, being designed for use where the fulcrum bar (discarded in the present instance) is of no use by reason of lack of available support opposed to the line of work to be accomplished. In other 75 words, while the form and arrangement of parts shown in the patent are effective and practicable for work at substantially right angles to the longitudinal axis of the actuating lever, the device is only available where 80 the fulcrum bar can be seated on an adjacent stationary part, and is not adapted for use as a club dolly positioned substantially in alinement with the longitudinal axis of the actuating lever A, as indicated for instance in Fig. 8, of the drawings in the present case. Hence, it is my purpose to equip 85 each actuating lever A, with a set of detachable adjuncts consisting of the fulcrum bar and jam dolly described in the aforesaid patent together with my new "spring club" dolly, so called, so as to render the 90 new commercial combination of parts adaptable to all the varying requirements of use. 95

With this understanding, my present riveting tool consists essentially of the actuating lever A, formed with the recessed socket head α^x , and my club dolly bar D, detachably combined therewith, the means of copulation being the same as those provided for the jam dolly and lever bar in the patent referred to. That is to say, bearings a , a' , are formed in the side walls of the lever socket head α^x , for the mounting thereon of bolts B, B', which are used to secure my club dolly D, in either position on the lever A, either that shown in Figs. 5 and 8, in substantial alinement with the longitudinal axis of the lever A, or at right angles thereto, as in Fig. 9, of the drawings. 100

To this end the body or shank d , of my club dolly bar D, is shaped to fit in snugly 105

between the side walls of the socket head α^x , and is formed with central bolt holes d' , d' , which coincide with the bolt bearings a , a' , in said head α^x , when the said shank d , is 5 positioned in said socket head α^x , in alinement with the length of the actuating lever A, as in Figs. 5, 6 and 8, and is also formed with the semi-circular edge recesses d^2 , d^2 , adapted to be brought into coincidence with 10 said bolt bearings a , a' , when the club dolly D, is positioned transversely between the side walls of the socket head α^x , at right angles thereto, as in Fig. 9,—the bolts B, B', when inserted and seated in the head α^x , in 15 either case securing the club dolly in position.

It may be stated in this connection that I prefer to form the dolly shank d , with semi-circular edge recesses d^2 , d^2 , as shown in 20 Figs. 3 and 4, of the drawings, but that annular recesses d^2 , d^2 , as in the modification shown in Fig. 10, may be resorted to with like result, so that I do not limit myself in this respect.

25 Only two central recesses or bolt holes d' , d' , are necessary for securing the dolly in alinement with the actuating lever A, because the latter can be moved freely horizontally to accommodate the dolly to the 30 work to be done in that direction; but as the lateral or vertical play of the actuating lever A, is comparatively limited, I provide the dolly shank d , with two or more pairs of edge bolt recesses d^2 , d^2 , so that the club 35 dolly bar D, may be made to protrude more or less laterally from the socket head α^x , as may be found most expedient in adapting it to the requirements of the work to be done.

The forward or contactual end of the club 40 dolly bar D, is formed with the usual or any suitable socket d^3 , for fitting over the previously formed head r' , of a rivet r , r^2 , representing the new head after finishing by the pneumatic hammer or other tool or 45 implement used for the purpose.

The bolts B, B', are obviously essentially coupling pins for sustaining the shank d , of the club dolly bar within the lever socket head α^x , and hence I do not limit myself to 50 screw bolts for this purpose. Cotter pin fastenings might be substituted for the screws and nuts shown, or other well known mechanical expedients might be resorted to without departing from the spirit and intent 55 of my invention in this respect. The screw bolts and nuts shown however represent operative means for accomplishing the results sought, which are, the assembling or disconnection of the parts in a convenient and 60 expeditious manner, so that the implement may be readily adjusted to various situations and conditions of use. It may be noted in this connection, that whereas in my former patent referred to one of the bolts B, 65 acted as a fulcrum, in the present case the

function of both bolts B, B', is simply to hold the club dolly D, rigidly in position on the socket head α^x , of the lever A.

When my club dolly bar D, is to be used in connection with the actuating lever A, the latter is fulcrumed on a stirrup s , attached to a suspender s' , adapted to be secured to any suitable or convenient stationary support above and adjacent to the location of the work to be accomplished. Obviously the attachment of the suspender s' , to a stationary overhead support is a matter of detail to which I am in no wise restricted, that indicated in Fig. 9, being shown only as one of many means and mechanical expedients that might be resorted to for the purpose. The fulcrum stirrup s , is preferably in the form of a hook as shown in Figs. 7 and 8, to facilitate the seating of the lever A, although an eye or link might be used instead through which the handle of the lever A, might be inserted. The suspender S' , to which the stirrup s , is attached, is preferably, but not necessarily flexible, a chain, or wire rope being suitable for the purpose, although I do not limit myself in this respect, the essential feature being the fulcrum s , on which the actuating lever A, may be seated in proximity to the work to be done.

95 It is obvious that thus equipped and seated the dolly-lever A, is adapted for use in situations and under conditions in which support from below is impossible; and that it is also thus rendered available in contracted spaces that would not otherwise be accessible. And the adaptability of my club dolly bar D, for use either substantially in alinement with the lever or laterally at right angles thereto, is also an important practical advantage which greatly increases the value, scope and utility of the implement.

100 Among iron workers a jam dolly is one that is jammed and actuated between opposed stationary supports, as illustrated in my aforesaid Letters Patent; while "spring club" dolly is a rod formed with a socket on one end, that is pressed directly against the head of a rivet to be supported. When 110 used as a "club" dolly the latter is positioned in alinement with the lever as in Fig. 8; when used as a "spring" dolly, it is positioned at right angles thereto, as in Fig. 9, and the "spring" is caused by bearing down 115 upon the handle of the lever.

120 What I claim as my invention and desire to secure by Letters Patent is,

1. An implement of the character designated, comprising a one-piece dolly bar formed with a socket for contacting with a rivet head and with coupling pin seats on its opposite edges, an actuating lever having a head for engagement with said dolly bar said lever head being formed with coupling pin bearings, coupling pins adapted 125 to

- to engage with said bearings in the lever head and with the coupling pin seats in said dolly bar, means for securing said coupling pins in position, and a fulcrum stirrup and 5 suspender for the support of said actuating lever, for the purpose described.
2. An implement of the character designated, comprising a one-piece dolly bar formed with a socket for contacting with a 10 rivet head and with plural series of coupling pin seats on its opposite edges whereby the said dolly bar may be supported in different positions on the actuating lever, said actuating lever having a head for 15 engagement with said dolly bar and formed with coupling pin bearings, coupling pins adapted to engage with said bearings in the lever head and with the coupling pin seats in said dolly bar, means for 20 securing said coupling pins in position, and a fulcrum stirrup and suspender for the support of said actuating lever, for the purpose described.
3. An implement of the character designated, comprising a one-piece dolly bar formed with a socket for contacting with a 25 rivet head and also formed with series of coupling pin seats on its opposite edges, an actuating lever having a recessed head 30 adapted to straddle said dolly bar, said head being formed with coupling pin bearings, coupling pins adapted to engage said bearings in the lever head and with the coupling pin seats in said dolly bar, means for 35 securing said coupling pins in position, and a fulcrum stirrup and suspender for the support of said actuating lever.
4. An implement of the character designated, comprising a one-piece dolly bar 40 formed with a socket for contacting with a
- rivet head and with a plural series of coupling pin seats on its opposite edges whereby the said dolly bar may be supported in different positions on the actuating lever, said actuating lever having a recessed head 45 adapted to straddle said dolly bar, said head being formed with coupling pin bearings, coupling pins adapted to engage said bearings in the lever head and with the coupling pin seats in said dolly bar, means for 50 securing said coupling pins in position, and a fulcrum stirrup and suspender for the support of said actuating lever.
5. An implement of the character designated, comprising a dolly bar formed with 55 a socket for contacting with a rivet head and with plural sets of coupling pin seats, the dolly bar constructed to be positioned in alinement with or at right angles on and as related to the actuating lever, said actuating lever having a head for engagement with said dolly bar, said lever head being formed with coupling pin bearings, coupling pins adapted to engage with said bearings in the lever head and with the coupling pin 60 seats in said dolly bar, and means for securing said coupling pins in position on the lever head, for the purpose described.
6. An implement of the character designated, comprising a one-piece dolly bar 65 formed with coupling seats on opposite edges, an actuating lever and connections adapting the dolly bar to be positioned in alinement with the said lever or at an angle thereto.
